UNITED STATES PATENT OFFICE.

MONROE GUETT, OF HARTFORD, CONNECTICUT, ASSIGNOR TO THE HART & HEGEMAN MANUFACTURING COMPANY, OF SAME PLACE.

DESIGN FOR A SWITCH CONTACT MEMBER.

SPECIFICATION forming part of Design No. 26,564, dated January 26, 1897.

Application filed October 20, 1896. Serial No. 609,470. Term of patent 14 years.

To all whom it may concern:

Be it known that I, MONROE GUETT, a citizen of the United States, residing at Hartford, county of Hartford, and State of Connecticut, 5 have invented and produced a new and original Design for Switch Contact Members, of which the following is a specification, reference being had to the accompanying drawings.

10 Figure 1 is a plan view of a switch contact member, showing my design. Fig. 2 is a section of the same on the line xx .

The leading feature of my invention consists in a somewhat shield-like outline, within 15 which is a slot forming two arms partially embracing a perforated center and connected together at their extremities, the outlines of said arms when viewed in elevation, as in Fig. 2, being of less thickness than the portion 20 immediately surrounding the perforation.

A is the central portion of the switch member, having a perforation G. B B' are arms partially embracing said central portion A. Between the central portion A and the arms 25 B B' is a slot C, so that the shape of the central portion conforms somewhat to the inner edges of the arms B B'. The arms B B' are connected at one end by an extended base D, which is connected to the central portion 30 A, and at the other end by a cross-head E. The arms B B' when viewed as in Fig. 2 are of less thickness than the central portion A.

What I claim is—

The design for a switch contact member, 35 substantially as described and shown.

MONROE GUETT.
